UNITED STATES PATENT OFFICE

WILLIAM E. WINE, OF TOLEDO, OHIO

BODY BOLSTER

Application filed April 9, 1928. Serial No. 268,726.

My invention relates to body bolsters for railway cars, and has for one of its objects, the production of a body bolster of simple and rugged construction capable of effectively withstanding buffing shocks transmitted to it from the car center sill.

A principal feature of the invention resides in providing a body bolster, adapted to be secured to opposite sides of the car center sill, 10 with a substantially vertical web and with a flange projecting on opposite sides of the latter adjacent the lower edge thereof, the flange being formed with auxiliary flanges spaced from said web and alternately serving as 15 compression and tension members to resist buffing shocks transmitted from the car center sill.

Another feature of the invention consists in constructing a railway car with a body 20 bolster provided with a substantially vertical web and with inner flanges adapted to be respectively secured to opposite sides of the car center sill, said inner flanges having auxiliary flanges spaced from said web.

25 Other and more specific features of the invention residing in advantageous constructions and combinations of parts will herein-after appear and be pointed out in the claims.

In the drawings illustrating a preferred 30 embodiment of the invention:

Figure 1 is a fragmentary transverse sectional view of a drop bottom railway car provided with the improved form of bolster.

Figure 2 is a plan view of one of the bolster 35 sections.

Figure 3 is a front elevational view of the bolster section illustrated in Figure 2.

Figure 4 is a bottom view of the same bolster section.

40 Figure 5 is an elevational view of the inner end of the bolster section, the upwardly projecting end thereof being omitted.

Figure 6 is a sectional view taken on line 6—6, Figure 3.

45 Figure 7 is a sectional view taken on line 7—7, Figure 3.

Figure 8 is a sectional view taken on line 8—8, Figure 3.

50 Referring to the drawings, 1 indicates the car side sills and 2 is the box-like center sill;

the latter being formed of a pair of spaced flanged members 3 having their webs 4 substantially parallel. Each of the center sill members 3 is fashioned with lower and upper flanges 5 and 6 respectively, the flanges 6 being connected by a longitudinally extending plate or cover member 7.

55 A filler casting 8 may advantageously be employed for connecting the web portions 4 of the center sill members 3 at the bolster. 60

The body bolster 9, instead of being formed as an integral casting is preferably constructed of 2 cast sections 10. Each of the bolster sections is provided with a substantially vertical web 11, having a plurality of apertures 12 to reduce the web of the bolster. 65 Adjacent the upper and lower edges of the bolster web 11 and projecting on opposite sides thereof, the bolster is fashioned with flanges 13 and 14 respectively, the upper flange being 70 connected to the web by an inclined portion 15. The lower flange 14 is wider than the upper flange 13 and its lateral edges converge from opposite sides of the center sill toward the respective outer ends of the bolster. 75

The bolster sections are also provided with inner substantially vertical flanges 16 which likewise project on opposite sides of the bolster web 11 and which are provided with a plurality of apertures 17 to receive rivets 80 for securing them to opposite sides of the car center sill 2. Projecting inwardly of the opposite sides of the center sill from each of the bolster sections, is an upstanding plate-like integral extension 18. Plate-like 85 members 19 may advantageously be employed for rigidly connecting the bolster sections, the plates being respectively disposed in overlapping relation to opposite sides of the extensions and secured thereto by rivets 20. 90

The upper portions of the bolster extensions are formed with flanges 21 and 22 which respectively are in substantial alinement with the flanges 13 and 15 of the main body portions of the bolster sections. 95

The lower portions of the bolster sections are preferably secured together by a bottom cover plate 23 which terminates adjacent the side bearing wear plate 24. The plate, in addition to being connected to the lower 100

flange 14 of the bolster sections by rivets 25, may also advantageously be connected to the respective bottom flanges 5 of the center sill members 3 by rivets 26. Adjacent to its opposite outer ends the bolster is fashioned with a flange 43, formed similarly to the inner flange 16, to which the side sills 1 may be connected. The lower flange 14 of each of the bolster sections inclines downwardly away from the adjacent side sill as at 27 and merges into an intermediate horizontal portion 28 affording a surface to which the side bearing wear plate 24 may be attached. From this point the lower flange 14 again inclines downwardly as at 29 toward the center sill, merging at the latter place into the inner vertical flange 16.

Any suitable center bearing may be employed for pivotally mounting the body bolster on the truck bolster, diagrammatically shown at 30, the upper part 31 of the center bearing being conveniently secured to the bottom cover plate 23 and a portion of the center sill. In the present instance, the outer ends of the bolster are fashioned with upwardly projecting portions 32, the top surfaces of which are inclined as at 33 to supportingly cooperate with the inwardly flanged portions 34 of the car side sheets 35. The side sheets are riveted as at 36 to upwardly flanged portions of the inclined floor sheet 37, the latter being supported by the upper flange of the bolster. Car side stakes 38 are respectively rigidly secured to the web 11 of the bolster by rivets 39 and project upwardly therefrom in overlapping relation to the inner surfaces of the respective side sheets. From the foregoing it will be seen that all parts of the car construction adjacent the bolster are effectively secured thereto and that, due to the normal load carried by the car, the bottom flange of the bolster is in compression, while the top flange thereof is in tension.

The bolster is provided with a plurality of truss-like flanges 40, projecting on opposite sides of the web 11 to effectively resist and efficiently distribute throughout the bolster the stresses normally imparted thereto by the car body and its contained lading. The truss-like flanges of the bolster sections extend from the outer lower corners thereof upwardly and inwardly to the upper flange 13, thence downwardly and inwardly toward the respective horizontal portions 28 to which the side bearing wear plates are attached, then again upwardly to the flange 13 and from there downwardly to the opposite upper corners of the center sill, there merging into the corresponding inner vertical flanges 16 of the bolster.

As is well known, buffing forces are communicated to the car center sill and from there are transmitted to the body bolsters

and thence into adjacent parts of the car construction.

Because of the inertia of the car body and because the outer ends of the bolster are securely anchored to the car side sills, the buffing forces communicated to the bolster induce bending stresses therein around axes extending outwardly from the center sill towards the sides of the car.

In all body bolster constructions, buffing shocks tend to bend the bolster on substantially vertical axes spaced outwardly of the center sill on opposite sides thereof and in bolster constructions having portions projecting above the center sill, the buffing shocks also tend to bend the bolster about horizontal axes.

To effectively resist these forces tending to bend the bolster around vertical axes, the lower flange 14 of the bolster is fashioned with substantially vertical auxiliary flanges 41; and to resist the forces tending to bend the bolster about horizontal axes, the inner flanges 16 are likewise provided with auxiliary flanges 42.

The auxiliary flanges 41 diminish in height from points adjacent opposite sides of the center sill towards the respective outer ends of the bolster where they may advantageously merge into the plane of the lower flange. Auxiliary flanges are unnecessary adjacent the side sills as at these points the bolster is practically in simple shear, the bending moments being a minimum. The truss-like flanges 40, which intersect at the horizontal portion 28 of the bolster form means 44 serving to tie together the auxiliary flanges 41, while the truss flanges which merge into the inner vertical flanges 16 likewise tie together the auxiliary flanges 42.

The auxiliary flanges 41 and 42 being on opposite sides of the web 11 of the bolster alternately serve as compression and tension members, depending on the direction of buffing shock transmitted from the car center sill, thus providing means effectively resisting all bending forces induced in the bolster by buffing shocks.

I claim:

1. A railway car body bolster having portions adapted to be secured to opposite sides of the car center sill, each of said portions being integrally formed with a substantially vertical web and with a flange projecting on opposite sides of the latter adjacent the lower edge thereof, said flange being integrally provided with auxiliary flanges spaced from said web and alternately serving as compression and tension members to resist buffing shocks transmitted from the car center sill.

2. A railway car body bolster having portions adapted to be secured to opposite sides of the car center sill and provided with a substantially vertical web and with a

lateral flange projecting on opposite sides of the latter adjacent the lower edge thereof, said flange being provided with correspondingly formed upstanding auxiliary flanges respectively spaced substantially equal distances from opposite sides of said web and alternately serving as compression and tension members to resist buffing shocks transmitted from the car center sill.

5 3. In a railway car body bolster having portions adapted to be secured to opposite sides of the car center sill, each of said portions being integrally formed with a substantially vertical web and with a bottom flange projecting on opposite sides of the latter, said flange being integrally provided with auxiliary flanges spaced from and substantially parallel to said web, said auxiliary flanges alternately serving as compression and 15 tension members to resist buffing shocks transmitted from the car center sill.

4. A railway car body bolster having portions adapted to be secured to opposite sides of the car center sill and provided with a substantially vertical web and with a flange projecting on opposite sides of the latter adjacent the lower edge thereof, said flange being provided with upwardly projecting auxiliary flanges spaced substantially equal distances 25 from the said web and diminishing in height from points adjacent opposite sides of the said center sill towards the respective outer ends of the bolster, said auxiliary flanges alternately serving as compression and tension 30 members to resist buffing shocks transmitted from the car center sill.

5. In a railway car body bolster having portions adapted to be secured to opposite sides of the center sill, each of said portions being integrally formed with a substantially vertical web and with a bottom flange projecting on opposite sides of the latter, said flange terminating in substantially vertical auxiliary flanges which merge into the plane of the said 40 flange inwardly of the outer ends of the bolster, said auxiliary flanges alternately serving as compression and tension members to resist buffing shocks transmitted from the car center sill.

50 6. A railway car body bolster involving a plurality of cast sections respectively adapted to be secured to opposite sides of the center sill, each of said sections having a substantially vertical web, the bottom of the bolster being of channel section and having its legs disposed on opposite sides of the said web, said legs alternately serving as compression and tension members to resist buffing shocks transmitted from the car center sill.

60 7. A railway car body bolster having portions adapted to be secured to opposite sides of the car center sill, each of said sections being integrally formed with a substantially vertical web and with a lower flange, the 55 lateral edges of said flange converging in-

wardly from the opposite sides of the car center sill toward the respective ends of the bolster, said flange being formed on opposite sides of said web with substantially vertical auxiliary flanges alternately serving as compression and tension members to resist buff- 70

8. A railway car body bolster having portions adapted to be secured to opposite sides of the car center sill and provided with a substantially vertical web and with upper and lower flanges projecting on opposite sides of the latter, the lower flange being wider than the top flange and being provided with auxiliary flanges spaced substantially equal distances from said web, the auxiliary flanges alternately serving as compression and tension members to resist buff- 75

9. A railway car body bolster provided with a substantially vertical web, and with inner flanges adapted to be respectively secured to opposite sides of the car center sill, said inner flanges being provided with auxiliary flanges spaced from said web. 80

10. A railway car body bolster provided with a substantially vertical web, and with inner flanges adapted to be respectively secured to opposite sides of the car center sill, said flanges terminating on opposite sides of the web in substantially vertical auxiliary flanges. 95

11. A railway car body bolster having inner flanges adapted to be respectively secured to opposite sides of the car center sill and provided with a substantially vertical web and with a bottom flange, said inner and bottom flanges projecting on opposite sides of the web and intersecting adjacent the car center sill, said inner flange being provided with auxiliary flanges spaced from said web. 100

12. A railway car body bolster having portions adapted to be secured to opposite sides of the car center sill and provided with a substantially vertical web and with upper and lower flanges projecting on opposite sides of the latter, said lower flange being provided with upstanding auxiliary flanges spaced from said web and alternately serving as compression and tension members to resist buffing shocks transmitted from the car center sill, said bolster being further provided with a plurality of truss-like flanges, two of said flanges intersecting adjacent the lower flange and serving as means for connecting said auxiliary flanges. 110

13. A railway car body bolster having inner flanges adapted to be respectively secured to opposite sides of the car center sill and provided with a substantially vertical web and upper and lower flanges projecting on opposite sides of the latter, said inner flanges being respectively provided with 120

130

auxiliary flanges spaced from said web, said bolster being further provided with truss-like flanges serving to connect said auxiliary flanges with the said upper flange.

- 5 14. A railway car body bolster having inner flanges adapted to be respectively secured to opposite sides of the car center sill and being provided with a substantially vertical web and with upper and lower flanges,
10 said inner and lower flanges terminating on opposite sides of the said web in substantially vertical auxiliary flanges, the latter alternately serving as compression and tension members to resist buffing shocks transmitted from the car center sill.

15 15. A railway car body bolster having inner flanges adapted to be respectively secured to opposite sides of the car center sill and provided with a substantially vertical
20 web and with upper and lower flanges, said inner and lower flanges projecting on opposite sides of said web and being respectively formed with auxiliary flanges, the bolster being further provided with a plurality of
25 truss-like flanges, the latter serving to connect the respective auxiliary flanges of each of said flanges.

16. A railway car body bolster section adapted to extend from the car center sill
30 to the car side sill, said bolster section being provided with a substantially vertical web and with a flange projecting on opposite sides of the latter adjacent the lower edge thereof, said flange being provided with auxiliary flanges spaced from said web and alternately serving as compression and tension members to resist buffing shocks transmitted from the car center sill.

17. In a railway car having a center sill,
40 a body bolster formed of a plurality of sections respectively secured to opposite sides of the center sill, each of said bolster sections being provided with a substantially vertical web and upper and lower flanges projecting on opposite sides of the latter, said lower flange being provided with correspondingly formed upwardly projecting auxiliary flanges spaced from said web and alternately serving as compression and tension members to resist buffing shocks transmitted from the car center sill.

In testimony whereof I affix my signature.
WILLIAM E. WINE.
